SLIDING WINDOW UNIT

Arthur E. Fisk, Pasadena, Calif., assignor of one-half to Frederick H. Ruppel, Pasadena, Calif.

Application March 6, 1933, Serial No. 659,599

19 Claims. (Cl. 189—64)

5 My invention relates to a window unit adapted to be completely pre-fabricated and to be placed bodily into a suitable recess provided therefor in a building frame structure, thereby eliminating a great deal of labor and time now expended in building window structures into the walls of buildings.

10 Many residences are now constructed with sliding sash adapted to be moved from the window opening into recesses provided in the wall at the sides thereof. These sash members are carried by tracks which must be properly aligned and supported in conjunction with the wall structure if a free movement of the sash between 15 closed and open positions is to be maintained.

15 It is well known that in lighter types of construction, such, for instance, as employed in residences, there is a settling or readjustment of the studs in the wall after the building has been completed for a period of time. Due to the load superposed thereon, a stud adjacent a window opening may move downwardly with the result that the horizontal members and other structural parts connected thereto are moved from 20 their original positions. In many instances this results in disalignment of the window structure so that the sliding sash will not move freely. It is a principal object of the present invention to avoid or compensate for such difficulties as above 25 set forth, by the provision of a completely pre-formed sliding sash window unit having a rigid metal frame defining a window opening and recesses or spaces at the sides thereof into which the sliding sash members may be moved.

30 It is a further object of the invention to provide a window unit of the above character so constructed that it may be installed in position within a wall structure without being tied to the wall framework. Where the invention is employed, a readjustment or settling of a stud or other frame member adjacent the window opening does not transmit strains to the frame in which the sliding sash members are carried, and in this manner binding of the sash due to 35 changes in position of the frame members of the building is avoided. Accordingly, it is an object of the invention to provide a window structure for use in a building wall in which frame members for the wall define an opening to receive the window unit, and a window unit held in such opening by means which engage the side faces of the window unit in a manner to prevent transverse movement of the window unit, but permitting a reasonable vertical and longitudinal relative movement of the window unit and

the wall frame members defining the opening in which the window unit is received.

It is a further object of the invention to provide a wall structure of the above general character in which the window unit is tied to the wall facing element, which facing element may readily consist of a layer of metal lath and plaster. In this construction the window unit floats in the frame structure of the wall but is definitely positioned and secured by being tied to the inner 10 and outer facings of the wall which are applied to the frame structure.

It is a further object of the invention to provide a window unit of simple, strong, and durable construction having a simple form of track 15 means and a novel means of adjustment for the tracks which will permit removal of one or all of the sash members as may be desired.

It is a further object of the invention to provide a novel and positive, but easily operated, 20 handle and latch means for the sash members of the window unit.

It is a further object of the invention to provide a sash element having a simple and efficient means for securing glass or screen in the sash 25 frames.

It is a further object of the invention to provide a window unit having a shutter sash equipped with a simple shutter structure adapted to be readily manipulated when the shutter 30 sash is in a position in the window opening, to permit entrance of light and air in the manner of a Venetian blind, but which may be locked in closed position so as to completely obscure the window opening.

35 A further object of the invention is to provide a window unit having a lower trackage therein and a lower wall so formed that natural drainage of water or other fluids will be accomplished.

Further objects and advantages of the invention will be made evident throughout the following part of the specification.

Referring to the drawings, which are for illustrative purposes only,

Fig. 1 is a perspective view of an embodiment 45 of the invention.

Fig. 2 is an enlarged, partly sectioned plan view of the window unit, with the protective cover plate of the unit removed.

Fig. 3 is a front elevation showing the window 50 unit in place in an opening provided therefor in the wall frame of a structure.

Fig. 4 is an enlarged fragmentary section on a plane represented by the line 4—4 of Fig. 3, showing the manner in which the wall facing 55

element is tied to the window unit, and also the manner in which the window unit is secured in the opening of the frame structure so as to be practically immovable in transverse direction.

5 Fig. 5 is an enlarged fragmentary section taken as indicated by the line 5—5 of Fig. 3, it being assumed that all of the sash members on the left-hand side of the window unit are in position to be intersected by the plane represented by the line 5—5.

10 Fig. 6 is a further enlarged fragmentary elevational view taken as indicated by the arrow 6 of Fig. 5.

15 Fig. 7 is an enlarged fragmentary section on a plane represented by the line 7—7 of Fig. 2.

Fig. 8 is an enlarged fragmentary section on a plane represented by the line 8—8 of Fig. 2.

20 Fig. 9 is an enlarged fragmentary elevational view showing the latch means for the sash members in engagement.

Fig. 10 is a fragmentary section on a plane represented by the line 10—10 of Fig. 9.

25 Fig. 11 is a fragmentary plan view showing the lower portions of a pair of sash members in engagement.

Fig. 12 is a fragmentary elevational view corresponding to Fig. 11.

30 The preferred embodiment of the window unit 20 is in the form of a rectangular prismatic structure 21 having a window opening 22 formed therein between end portions 23 which are hollow so as to form spaces or recesses 24, as shown in Fig. 4, within the end portions 23 which lie on opposite sides of the window opening 22 and are 35 in communication with the opening 22 through vertically elongated portals 25 formed between vertical frame members 26 and 27 which are preferably of rectangular tubular cross section. The window unit 20 is shown with sheet metal 40 side walls 28 covering the end spaces 24, but it is to be understood that such side walls are employed principally to protect the spaces 24 from entrance of moisture, plaster, or other foreign materials thereto, and such coverings 28 are 45 not necessarily part of the frame structure 30 which includes the members 26 and 27 and defines the window opening 22 and the spacers 24 at the sides thereof.

50 As shown in Figs. 2 and 7, the frame structure 30 employs a pair of upper horizontal frame members 31 and 32 which extend across the upper part of the window opening 22 and to the ends of the spaces 24. On opposite sides of the window opening 22, the vertical frame members 27 extend downwardly from the frame member 32 to a lower horizontal frame member 33 best shown in Figs. 4 and 5. This horizontal frame member 33 extends the full length of the window unit structure 21 and defines the lower 55 boundary of the leftward or inner portion of the window opening 22. From the lower ends of the vertical frame members 26 which extend downwardly from the upper horizontal frame member 31, horizontal frame members 34 extend outwardly within the lower forward parts of the spaces 24. The frame members 34 do not project into the window opening 22 but extend only into the side spaces 24. As shown in Fig. 5, the members 35 are disposed in a plane below the plane of the member 33, and extending across the lower 60 faces of the members 33 and 35, a lower wall 36 of sheet metal is secured in any desired manner, as by spot welding. It is a feature of the invention to slope this bottom wall 36 outwardly and 65 downwardly in the direction of the arrow 37 of

Fig. 4, or in leftward direction as shown in Fig. 5. The central portion 38 of the wall 36 disposed within the window opening 22 is extended outwardly in the direction of the arrow 37 beyond the outer faces of the vertical members 26 so that the forward edge 40 of the central portion 38 will project at least as far as the surface 41 of a wall finishing element 42, shown in the present disclosure of the invention as consisting of a web or layer of metal lath 43 and plaster 44. 10 If desired, the ends of the lower wall 36 may be slightly raised so that such end portions of the wall 36 will slope toward the central portion 38 as well as forwardly. It is preferable that the wall 36 be made in one continuous piece as it 15 forms a means for draining from the interior of the window unit any liquids which may enter the same.

Extending substantially throughout the entire length of the window unit, a lower track member 20 45 is secured in a position slightly raised above the lower wall 36 by means of spacer blocks 46 secured in place by use of screws 47. The lower track member provides three upwardly projecting ribs or rails 48 connected together by lower 25 walls 50 which extend under channels 51 by which the rails 48 are separated. The sides of the track member 45 are formed to provide laterally extending flanges 52 which engage or are 30 proximate to the inner faces of the longitudinal frame members 33, 34, and 35. Above the flanges 52 are channels 53 which are approximately half the width of the channels 51. For the drainage of the channels 51, openings 55 are formed in the lower walls which interconnect the rails 48. 35 Accordingly, any water which enters the channels 51 will drain through the openings 55 and will then flow to the exterior along the upper face of the lower wall 36.

An upper track member 56 is extended longitudinally through the upper portion of the structure 21, between the upper frame members 31 and 32, as shown in Figs. 2 and 7. This upper track member 56 is of the same cross sectional form as the track member 45 but is inverted so that the three rails or ribs 48' thereof project downwardly. The frame members 31 and 32 are connected together by cross bars or plates 57 and 58, the ends of which are secured to the members 31 and 32 by spot welding or other suitable means. 50 As shown in Fig. 7, each of the cross bars 57 has a block 60 secured to the under face thereof provided with a vertical opening 61 within which the cylindrical shank 62 of a screw 63 extends, there being a flat-headed screw 64 threaded into 55 the upper end of the shank 62 to prevent removal thereof from the opening 61. The lower end of the screw 63 is threaded through an opening 65 in the central rib 48'. In the form of the window unit shown, two of the screws 63 are employed, and by rotating the same by application of a screw-driver to the lower slotted ends thereof, the upper track member 56 may be caused to move vertically for the purpose of adjustment. Vertical guide means for the track member 56 60 are formed by the cylindrical shanks 66 of screws 67 which extend downwardly from blocks 68 mounted on the lower faces of the cross bars 58. Openings 70 are formed in the central rib 48' of the member 56 to receive the shanks 66 of the 70 screws 67, there being counterbores 71 formed in the lower ends of the openings 70 to receive the heads 72 of the screws 67.

In the form of window unit shown, three lower tracks 48 and three upper tracks 48' are pro- 75

vided for supporting and guiding three pairs of sash members 73, 74, and 75, each of which comprises an essentially rectangular frame disposed between upper and lower rails 48 and 48' so as to be slideable between open and closed positions relative to the window opening 22. When the sash members 73, 74, and 75 are in open position, they rest within the side spaces 24 as shown in Figs. 1 and 4. As shown in Fig. 5, the lower horizontal members 76 and 77 of the sashes each provide a horizontal wall section 78, from the edges of which webs 80 extend downwardly on opposite sides of the ribs 48. In the channels 81 formed between the webs 80, rollers 82 are mounted on shafts 83 so as to engage the upper faces of the ribs and to enable a free rolling movement of the sashes 73, 74, and 75 in the window unit structure 21. As shown in Fig. 7, the sashes 73, 74, and 75 have upper horizontal members 76' and 77' which are of the same cross section as the members 76 and 77 shown in Fig. 5 but are inverted so that the side webs 80 thereof will project upwardly on opposite sides of the ribs 48' of the upper track 56. Although rollers are not shown in the upper members 76' and 77', they may be employed as desired or as conditions may require.

As shown in Fig. 4, the sashes 73 and 74 have inner and outer vertical members 84 and 85 connecting the ends of the upper and lower horizontal members 76 and 76', and the sashes 75 have inner and outer vertical members 86 and 87 connecting the ends of the horizontal members 77 and 77'. Each of the members 84, 85, 86, and 87 may, like the members 76 and 77, be of channel-shaped cross section. The inner vertical members 84 and 86 of the left-hand set of sashes 73, 74, and 75, as shown in Fig. 4, have vertical cover plates 90 secured to the outer edges of the webs 80 thereof, each of the plates 90 having a vertical rib 91. The inner vertical members 84 and 86 of the right-hand set of sash members 73, 74, and 75 have cover plates 90' secured in the outer edges of the walls 80 thereof, such cover plates 90' being provided with vertical ribs 91' adapted to overlap the ribs 91 when the sashes are in closed position so that the cooperating pairs thereof engage on a central plane through the window opening 22. In Fig. 11, the right-hand and left-hand sashes 73 are shown in engagement in the central plane defined by a stop member 93 in the form of a rectangular block secured to the lower track member 45 by means of screws 94. The lower ends 95 of the vertical cover strips 91 and 91' are disposed proximate to the upper face of the block 93 when the sash members are in closed position.

Each of the left-hand set of sashes is provided with a projecting loop or handle 97, and each of the right-hand sashes is provided with a projecting loop or handle 98, these handles being in the same horizontal plane, but, as shown in Fig. 10, the respective handles 97 and 98 are disposed in different vertical planes so that the handles 97 will pass the handles 98 and enter recesses 100 formed in the front vertical members 84 and 86 of the right-hand sashes, while the handles 98 pass into the recesses 101 formed in the forward vertical members 84 and 86 of the left-hand sashes. As shown in Fig. 10, suitable openings 102 and 103 are provided in the vertical cover strips 91 and 91', through which the handles 97 and 98 may enter the recesses 100 and 101. As shown in Figs. 3, 9, and 10, vertically elongated openings 104 and 105 are formed in the inner webs 80 in alignment with the handles 97 and

98. In each recess 100 a latch member 106 is pivotally mounted, this latch member comprising a plate 107 having its leftward end 108 seated in a suitable socket 110 formed in the member 91' adjacent the opening 102. In a position to engage 5 the vertical portion 111 of the loop or handle 97, the plate 107 is provided with a shoulder 112. A spring 113 behind the latch member 106 urges the same forwardly toward its engagement position, this forward movement being limited by a stop 114. When a pair of cooperating sash members are in closed position, as shown in Figs. 9 and 10, the latch means 106 will operate to prevent movement of the sash members from closed position. The latch means, however, may be readily released from the inside by pressing outwardly 10 on a tongue 115 which extends forwardly from the rightward or swinging end of the latch 106. 15

An additional feature of the invention resides in the simple means provided for securingment of 20 panes of glass 117 in the sash members 73 and 74 and screens 118 in the sash members 75, the securing means of the frames 73 and 74 being identical and being adapted for use with a sheet member consisting of either glass or screen. The vertical 25 and horizontal members 84, 85, 73, and 76' forming the sashes 73 and 74 have, as shown to enlarged scale in Fig. 10, inwardly directed major flanges 120 and minor flanges 121 defining channels 122 adapted to receive securing strips 123. 30 The major flanges 120 are provided with grooves 124 facing the channel 122, and the minor flanges 121 are formed with inwardly facing lips 125. The securing strips 123 have edges 126 formed to fit under the lips 125, and along the sides thereof 35 opposite to the edges 126 are provided with relatively sharp edges 127 aligned with the grooves 124. Each securing strip has a shoulder 128 which cooperates with the edge portion 130 of the adjacent major flange 120 to form a channel 132 40 adapted to receive the edge of a pane of glass together with a body of putty 133 in which the edge of the glass is secured.

The process of mounting the pane of glass is substantially as follows: The sash 73 is laid upon 45 a table with the major flange 120 down. A layer of putty is then placed upon the upper face of the major flange, after which the glass 117 is placed in the opening of the sash with the edges thereof resting upon the initially applied layer of putty. A strip of putty is then laid along the edge of the glass, and the securing strip 123 is then forced into the upper part of the channel 122, the edge 126 thereof engaging under the lip 125. By use of a putty knife, the soft putty projecting 50 along the edges of the glass is pressed into the channel 122, and the glass is thus secured in the sash in a strip of putty without touching the metal parts of the sash.

The screen 118 is secured in a frame 74 by placing 60 such screen 118 in the frame so that the edges thereof overlie the major flange and the groove 124 therein. The securing strip 123 is then forced into the channel 122, with the result that the sharp edge 127 thereof forces the edge of the 65 screen into the groove 124, thereby firmly securing the screen.

My new window unit also provides a simple and efficient shutter structure 140 mounted in the outer or shutter sashes 75. This shutter structure consists, as shown in Figs. 3, 5, 6, and 7, of a plurality of horizontal strips 141 of metal having their upper edges 142 bent inwardly at essentially an angle of 45°, as shown in Fig. 7. On the ends of the strips 141 adjacent the upper bent edge 75

portions 142 thereof, pins or trunnions 143 are projected horizontally into holes 144 in the walls 145 of the vertical members 86 and 87 of the sashes 75. On these pins 143 the strips 141 may 5 be swung outwardly from the vertical positions in which they are shown in full lines in the figures to diagonal positions as indicated by dotted lines 146 in Fig. 7. For controlling the movement of the members 141, I provide an actuating bar 147 10 which extends vertically at one side of the sash opening and across the edges of the diagonally bent portions 142. This actuating bar is pivotally connected to each inwardly bent portion, which may be accomplished by means of small rings or 15 loops 148 mounted on the actuating bar 147 and passing through openings in the edge portions 142. The bent portions 142 of the members 141 are then caused to act as levers by which the members 141 may be swung between closed and 20 open positions. By moving the actuating bar 147 downwardly from the position in which it is shown in Figs. 5 and 7, the shutters or members 141 may be swung toward open position.

As shown in Figs. 5 and 6, a simple latch 25 means is provided for controlling the position of the actuating bar 147, this latch means consisting of a small block 150 having a shoulder 151 near its upper end adapted to be engaged by a pawl 152 on the lower end of the actuating 30 bar 147 when the actuating bar is raised to its highest position and the shutter strips 141 are closed. The block 150 has a series of notches 153 below the shoulder 151 adapted to be engaged by the pawl 152 on the bar 147 when the bar 35 147 is moved downwardly. A spring 154 is provided adjacent the notches 153 and engages the lower end of the bar 147 in a manner to force the same toward the block 150. For operation of the actuating bar 147, a small handle 155 is 40 provided thereon so that the lower end of the bar 147 may be moved outwardly or rightwardly relative to the block 150 and then downwardly to a desired position of adjustment, giving a desired degree of opening of the shutters 141. 45 When the shutters 141 are in closed position, the lower edges 157 thereof overlap the bent edge portions 142 of the downwardly succeeding shutters so that a continuous wall is formed. When the shutters 141 are swung into open position, they resemble the commonly employed Venetian blind, holding out the sunlight but permitting a relatively free passage of air. When 50 use of the shutter sashes is not desired, they may be moved into concealment in the side spaces 55 148 thereby removing them from view which is an improvement over the common type of shutter construction in which the shutter members are hinged at the sides of a window opening and are swung back against the outer face of 60 the building when not in use.

In addition to the side covering sheets 28, the frame structure 30 may be further enclosed by a top sheet of metal 158 across the upper frame members 31 and 32 and by end sheets 160 for 65 closing the end of the window unit. These end walls 160 may be extended downwardly so that the lower ends 162 thereof will provide legs on which the window unit may stand. For handling the window unit 20, a strap or handle 163 is secured to the top thereof by means of rivets 164, one of which rivets passes through a slot 165 which permits the handle to be flattened when force is applied thereon, without transmitting a distorting force to the structure of the window 70 unit.

The window unit is employed in the following manner. As shown in Fig. 3, a rectangular opening 170 is formed in the frame structure of a building between studs 171 which extend vertically between a floor sill 172 and a plate 5 173. The upper and lower limits of the opening 170 are defined by horizontal members 174 and 175, the member 175 being carried on posts 177. The horizontal member 175 is preferably placed level in the installation thereof, and the 10 member 174 is placed at such distance thereabove that when the window unit 20 is placed in the opening 170, the handle 163 will pass freely under the member 174. The member 163, therefore, determines the height of the opening 15 170 and assures that the member 174, should it be deflected due to superimposed loads will not press against the main structure of the window unit and cause a deformation thereof. The handle is so constructed that should the member 20 174 be deflected downwardly, the handle will be flattened without producing a deformation of the window unit structure. The length of the opening 170 is slightly greater than the length 25 of the window unit so that the end walls 160 of the window unit will not engage the studs 171 and so that spaces 178 will be left therebetween. If desired, layers of felt or other resilient material may be placed in the spaces for the purpose of temporary spacing, but this is not necessary. 30 After the window unit is placed in the window opening 170, its removal is prevented by the application of stops 180 in the ends thereof preferably consisting of small vertical channels secured by nails 181 within the edges of the studs 35 171, as shown in Fig. 4. The members 180 engage side faces of the window unit so as to limit the transverse movement of the window unit so that the window unit cannot be moved out of the opening 174. The members 180, however, 40 do not interfere with a relative movement of the window unit and the building frame structure in a direction parallel to the plane of the wall defined by the frame structure. Therefore, a downward movement of the frame members 171, 45 174 and 175 after completion of the wall will not place distorting stresses on the window unit.

A feature of the invention is to provide a wall structure having a window unit therein which is prevented from transverse movement by stops 50 secured to the frame structure and which is tied to the facing element or elements of the wall, such as the latch 43 and plaster 44 shown in Fig. 4. As shown in this figure, the side walls 28 may be bent outwardly at 182 and 183 to provide a 55 border flange or border member around the window opening 22 to which the wall facing element may be secured. One method of securing the wall facing element 42 is to place strips of wood 184 around one of the border flanges 182, securing 60 these strips in place by means of screws 185. The metal lath is then carried across the outer faces of the studs and other structural members, and across the outlying or peripheral portions of the window unit, to be secured at 186 to the 65 rectangular frame consisting of the members 184. The outer edge of the border flange 182 then serves as a plaster stop around the opening. In addition to being tied to the window unit at the border of the window opening, the wall element is also tied to the sides 28 by use of metal fins 187 having flanges 188 whereby they may be secured to the side walls or plates 28 by spot welding. These fins 187 are provided with openings 189 through which wire loops 191 are passed 70 75

for the purpose of transversely supporting the metal lath 43, at least until the plaster 44 is applied. The wire loops 191 permit such slight relative movement of the wall facing element 42 and the window unit that changes in form due to expansion and contraction will not cause cracking of the plaster. After application of the wall facing element or elements 42, the window unit is rigidly secured in operative position without the window unit being tied to the building frame in such a manner that movement of one or more of the building frame members will distort the window unit so as to either move the window unit from horizontal position or dis-align the upper and lower tracks in such a manner that the sashes will bind therein. For example, after completion of the building, a second story load applied to one of the studs 171 may cause the same to recede a short distance. This downward movement of the stud will not in any way affect the window unit, for it has no direct engagement with the window unit which will continue to be supported on the horizontal member 75 or by the wall facing element or elements 42.

The window unit 20 has very pronounced weatherproof features due to the construction thereof, so that when the sashes are in closed position, a very effective closure of the window opening 22 is accomplished. As shown in Figs. 11 and 12, pins 200 are projected upwardly near the center of the inner rib or rail 48. When the inner sashes 73 are moved into closed position, the pins 200 are engaged by projections 201 formed on the inner faces of the webs 80 at the lower edges of the sashes 73, as shown in Fig. 5. The engagement of the projections 201 with the pins 200 is effective to move the lower portions of the sashes 73 inwardly so that the webs 80 will rest against the outer vertical faces of the lower frame member 33.

Although I have herein shown and described my invention in simple and practical form, it is recognized that certain parts or elements thereof are representative of other parts, elements, or mechanisms which may be employed in substantially the same manner to accomplish substantially the same results; therefore, it is to be understood that the invention is not to be limited to the details disclosed herein but is to be accorded the full scope of the following claims.

I claim as my invention:

1. A window structure of the character described, including: a wall frame having an opening formed between a pair of laterally spaced vertical members and upper and lower horizontal members spaced apart vertically; a window unit in said opening of said wall frame, resting on said lower horizontal member, said window unit being of such size relative to said opening as to leave spaces between the ends of said unit and said vertical members and a space between the top of said unit and said upper horizontal member; and means for holding said unit in said opening whereby only the transverse movement of said unit in said wall opening is restrained.

2. A window structure of the character described, including: a wall frame having an opening formed between a pair of laterally spaced vertical members and upper and lower horizontal members spaced apart vertically; a window unit in said opening of said wall frame, resting on said lower horizontal member, said window unit being of such size relative to said opening as to leave spaces between the ends of said unit and said

vertical members and a space between the top of said unit and said upper horizontal member; means for holding said unit in said opening, consisting of members so placed as to limit only the transverse movement of said unit in said wall opening; and a wall facing element extending across said vertical and horizontal members of said wall frame and being tied to said window unit.

3. A window structure of the character described, including: a wall frame having an opening formed between a pair of laterally spaced vertical members and upper and lower horizontal members spaced apart vertically; a window unit in said opening of said wall frame, said window unit being of less width and height than said opening of said wall frame; and means for holding said window unit in said opening, consisting of means extending from said wall frame and across the side faces of said window unit so as to limit transverse movement of said unit and permit a degree of free movement of said window unit in the vertical plane defined by said wall frame in order that movement of the members of said wall frame will not distort said window unit.

4. A window structure of the character described, including: a wall frame having an opening formed between a pair of laterally spaced vertical members and upper and lower horizontal members spaced apart vertically; a window unit in said opening of said wall frame, said window unit being of less width and height than said opening of said wall frame and having a window opening defined by a border member; means for holding said window unit in said opening, consisting of means extending from said wall frame and across the side faces of said window unit so as to limit transverse movement of said unit and permit a degree of free movement of said window unit in the vertical plane defined by said wall frame in order that movement of the members of said wall frame will not distort said window unit; and a wall facing element extending from said members of said wall frame and across the peripheral portion of said window unit to said border member, said wall facing element being tied to said border member of said window unit in such a manner that the position of said window unit is controlled by said wall facing element.

5. A window structure of the character described, including: a wall frame having an opening formed between a pair of laterally spaced vertical members and upper and lower horizontal members spaced apart vertically; a window unit in said opening of said wall frame, said window unit being of less width and height than said opening of said wall frame and having a window opening defined by a border member; means for holding said window unit in said opening, consisting of means extending from said wall frame and across the side faces of said window unit so as to limit transverse movement of said unit and permit a degree of free movement of said window unit in the vertical plane defined by said wall frame in order that movement of the members of said wall frame will not distort said window unit; and a wall facing element consisting of a web of lath and plaster, extending from said members of said wall frame and across the peripheral portion of said window unit to said border member, said wall facing element being tied to said border member of said window unit in such a manner that the position of said window unit is controlled by said wall facing element.

dow unit is controlled by said wall facing element.

6. A window structure of the character described, including: a wall frame having an opening formed between a pair of laterally spaced vertical members and upper and lower horizontal members spaced apart vertically; a window unit in said opening of said wall frame, said window unit being of less width and height than said opening of said wall frame and having a

10 window opening defined by a border member; means for holding said window unit in said opening, consisting of means extending from said wall frame and across the side faces of said window unit so as to limit transverse movement of

15 said unit and permit a degree of free movement of said window unit in the vertical plane defined by said wall frame in order that movement of the members of said wall frame will not distort said window unit; a wall facing element extending

20 from said members of said wall frame and across the peripheral portions of said window unit to said border member, said wall facing element being tied to said border member of said window unit in such a manner that the position 25 of said window unit is controlled by said wall facing element; and means for securing said wall facing element to the peripheral portions of said window unit.

7. A window structure of the character described, including: a wall frame having an opening formed between a pair of laterally spaced vertical members and upper and lower horizontal members spaced apart vertically; a window unit in said opening of said wall frame, said window unit being of less width and height than said

30 opening of said wall frame and having a window opening defined by a border member; means for holding said window unit in said opening, consisting of means extending from said wall frame and across the side faces of said window unit

35 so as to limit transverse movement of said unit and permit a degree of free movement of said window unit in the vertical plane defined by said wall frame in order that movement of the members of said wall frame will not distort said window unit; a wall facing element extending from

40 said members of said wall frame and across the peripheral portions of said window unit to said border member, said wall facing element being tied to said border member of said window unit in such a manner that the position of said window 45 unit is controlled by said wall facing element; and means for yieldably securing said wall facing element to the peripheral portions of said window unit.

50 8. A window unit of the character described, including: a frame defining a window opening and spaces at the ends of said opening and communicating therewith; closure members adapted to be moved from said spaces into said opening; lower track means for said closure members, said lower track means extending across said opening and into said spaces; and upper track means for

55 said closure members, said upper track means extending across the upper part of said opening and into the upper parts of said spaces, there being adjustment means for bodily raising and lowering said upper track means.

9. A window unit of the character described, 60 including: a frame defining a window opening and spaces at the ends of said opening and communicating therewith; closure members adapted to be moved from said spaces into said opening; lower track means for said closure members, said lower track means extending across said

65 opening and into said spaces; upper track means for said closure members, said upper track means extending across the upper part of said opening and into the upper parts of said spaces, there being adjustment means for bodily raising and lowering said upper track means;

70 opening and into said spaces; upper track means for said closure members, said upper track means extending across the upper part of said opening and into the upper parts of said spaces, there being adjustment means for bodily raising and lowering said upper track means; and a wall under said lower track means disposed so as to drain said spaces through the lower part of said window opening.

10. A window unit of the character described, 10 including: a frame defining a window opening and a space at the side of said opening and communicating therewith; a closure member adapted to be moved from said space into said opening; lower track means for said closure member, said lower track means extending across said opening and into said space; and upper track means for 15 said closure member, said upper track means extending across the upper part of said opening and into the upper part of said space, there being 20 adjustment means for bodily raising and lowering said upper track means.

11. A window unit of the character described, including: a frame defining a window opening and a space at the side of said opening and communicating therewith; a closure member adapted to be moved from said space into said opening; lower track means for said closure member, said lower track means extending across said opening and into said space; upper track means for said closure member, said upper track means extending across the upper part of said opening and into the upper part of said space, there being adjustment means for bodily raising and lowering said upper track means.

12. A window unit of the character described, including: a frame defining a window opening and spaces at the ends of said opening and communicating therewith; closure members adapted to be moved from said spaces into said opening; lower track means for said closure members, said lower track means disposed so as to drain said space through the lower part of said window opening.

13. A window unit of the character described, 30 including: a frame defining a window opening and spaces at the ends of said opening and communicating therewith; closure members adapted to be moved from said spaces into said opening; track means for guiding the movement of said closure members so that the adjacent edges thereof will engage when said closure members are in closed position; a handle extending from the adjacent edge of each of said closure members toward the edge of the other of said closure members, there being a recess in the edge of each closure member to receive the handle of the other closure member; and lock means operative in one of said recesses to engage the handle of the other closure member, whereby to hold said closure members in closed position.

14. A window unit of the character described, 40 including: a frame defining a window opening and spaces at the ends of said opening and communicating therewith; closure members adapted to be moved from said spaces into said opening; track means for guiding the movement of said closure members so that the adjacent edges thereof will engage when said closure members are in closed position; a handle for each of said closure members formed by a loop extending from the adjacent edge of each of said closure members toward the edge of the other of said closure members, there being a recess in the edge of each closure member to receive the handle of the other closure member; and lock means operative in one of said recesses to engage the outer part of the 50 loop therein, whereby to lock said closure members in closed position obstructing said window opening.

15. A window structure of the character described, including: a wall frame having an open- 55

ing formed between a pair of laterally spaced vertical members and upper and lower horizontal members spaced apart vertically; a window unit in said opening of said wall frame, there being spaces between the ends of said unit and said vertical members and a space between the top of said unit and said upper horizontal member; and means for securing said window unit in said opening so as to have restricted movement

10 in transverse direction relative to said wall frame and a free limited upward and horizontal movement relative to said wall frame in the direction of the vertical plane defined by said wall frame.

15. A window unit of the character described, including: a frame defining a window opening and spaces at the ends of said opening and communicating therewith; closure members adapted to be moved from said spaces into said openings; lower track means for said closure members, said 20 lower track means extending across said opening and into said spaces; and upper track means for said closure members, said upper track means extending across the upper part of said opening, there being adjustment means for bodily raising 25 and lowering said upper track means.

16. A window unit of the character described, including: a frame defining a window opening and spaces at the ends of said opening and communicating therewith; closure members adapted 30 to be moved from said spaces into said opening; lower track means for said closure members, said lower track means extending across said opening and into said spaces; and upper track means for said closure members, said upper track means 35 extending across the upper part of said opening, there being adjustment means for vertically moving said upper and lower track means relatively together and apart.

17. A window unit of the character described, 40 including: a frame defining a window opening and spaces at the ends of said opening and communicating therewith; closure members adapted to be moved from said spaces into said opening; track means for guiding the movement of said 45 closure members so that the adjacent edges

thereof will engage when said closure members are in closed position; a handle extending from the adjacent edge of one of said closure members toward the edge of the other of said closure members, there being a recess in the edge of said other closure member to receive said handle; and lock means operative in said recess to engage said handle, whereby to hold said closure members in closed position.

18. A window structure of the character described, including: a wall frame having an opening formed between a pair of laterally spaced vertical members and upper and lower horizontal members spaced apart vertically; a window unit in said opening of said wall frame, resting on 10 said lower horizontal member, there being spaces between the ends of said unit and said vertical members and a space between the top of said unit and said upper horizontal member, said window unit having a member resiliently disposed thereon for indicating the height of said opening, said resilient member being so formed and placed as to be deformable by a change in position of said members of said wall frame without application of distorting stresses to said window unit; and means for holding said unit in 15 said opening.

19. A window unit of the character described, including: a frame defining a window opening and a space at the side of said opening communicating therewith, said frame having a bottom wall extending across said opening and said space; a closure member adapted to be moved from said space into said opening; lower track 30 means for said closure member, said lower track 35 means extending across said opening and into said space and projecting above said bottom wall whereby drainage may occur across said bottom wall from one side of said track means to the other; an upper track means for said closure member, said upper track extending across the upper part of said opening and into the upper part of said space.
